VACUUM CLEANER

Dewey M. Dow, Toledo, Ohio, assignor to Air-Way Electric Appliance Corporation, Toledo, Ohio, a corporation of Delaware

Application July 10, 1936, Serial No. 89,965

8 Claims. (Cl. 15—16)

This invention relates to vacuum cleaners and has as its object to provide improvements in means controlled from the upper end of the handle for adjusting the height of the cleaner nozzle. The invention deals particularly with a type of cleaner in which the fan case is rigidly secured to the handle and swings therewith around the axis of rotation of its impeller on which axis the fan case and handle are pivoted to the remainder of the cleaner. One object of the invention is to provide a handle controlled height adjustment of a practical nature in connection with a cleaner of this type. To this end, the invention specifically contemplates the use of a control element in the form of a flexible wire or cable extending through the handle and around the spiral periphery of the fan case which acts as a slideway for such wire or cable, in connection with height adjusting means which is disposed beneath the fan case and, therefore, at least partially concealed.

Another object of the invention is to provide an arrangement in which the position of adjustment may be indicated at the upper end of the handle.

Further objects will appear in the perusal of the following detailed description of the invention in connection with the accompanying drawings in which:

Fig. 1 is a side elevation of a vacuum cleaner embodying the invention.

Fig. 2 is an enlarged detail view of portions thereof.

Fig. 3 is a cross section taken on the line 3—3 of Fig. 2.

Fig. 4 is a cross section taken on the line 4—4 of Fig. 2.

Fig. 5 is a cross section taken on the line 5—5 of Fig. 2.

Fig. 6 is a detail view of a modification of the invention.

Fig. 7 is a rear elevation of the mechanism shown in Fig. 6.

Fig. 8 is a detail view of another modification of the invention.

Fig. 9 is a sectional view taken on the line 9—9 of Fig. 8.

Fig. 10 is a view similar to Fig. 6 of another modification of the invention.

Fig. 11 is a sectional view taken on the line 11—11 of Fig. 10, and

Fig. 12 is a view similar to Fig. 6 of another modification of the invention.

The type of cleaner to which the invention is particularly adapted embodies the suction chamber 10 having a downwardly opening agi-

tator chamber or a nozzle portion 11 and two upwardly opening throat portions 12 to which are secured elbows 13. The fan case 14 is pivoted between the elbows 13 and has inlets communicating therewith. The handle 15 is secured to the fan case 14 by means of a saddle 16 which is concealed within a cape member 17 frictionally secured thereto.

The construction just described is similar to that disclosed in my prior application S. N. 84,072 filed June 8, 1936.

The cleaner is supported upon front wheels 18 and rear wheels 19, the latter being attached to a rear wheel bracket 20 which is hinged at 21 to the throat member 12 as by means of hinge 15 brackets 22.

The invention in the form shown in Fig. 2 provides a rider 23 disposed on an arc concentric to the axis of pivotal movement of the fan case and engaging a roller 24 rotatably mounted on the bracket 20. The rider 23 is attached to the fan case by means of toggle links 25 pivoted to the fan case at 26 and to the rider 23 at 27. The toggle links 25 connect the rider 23 to the fan case in such a manner that the rider may swing in a direction which is compounded of circumferential and radial movements. The movement in an outward direction is induced by pulling the rider in a circumferential direction by means of the flexible wire or cable 28 which is attached at one end to the rider and at its other end after extending around the periphery of the fan case and through the handle 15, is wound upon a reel 29 journaled in the upper end of the handle. The rider is urged in the other direction by a spring 30, one end of which is attached to the fan case at 31, and the other end of which is attached to the rider at 27.

The end regions of the rider 23 are slotted (as shown for the modification in Fig. 7) to receive the peripheral bead portion 32 of the fan case. This provides a sliding connection which holds the rider against lateral movement and yet allows it to move circumferentially. The rider is preferably channel shaped in cross section, the trunnions 27 of the toggle links 25 being journaled in the side flanges of the channel and the spring 30 being received in the space within the channel.

The reel 29 is provided with an operating wheel 50 or the like 33 which has an indicating dial 34 cooperating with an indicating arrow 35 on the handle to indicate the position of adjustment. In accordance with the position of the wheel the reel 29 will determine the circumferential position 55

of the wire 28 and the rider 23 and, therefore the radial position of the rider 23. The rider being disposed on an arc concentric with the axis of swinging movement of the handle may ride 5 against the roller 24 without disturbing the adjustment of the bracket 20 which is determined in accordance with the radial position of the rider 23. Thus the handle may be moved during the operation of the cleaner without interfering in any way with the adjustment of the nozzle which may, nevertheless, be instantly altered by the control mechanism carried by the handle.

Instead of the toggle links 25, the invention 15 may provide cams 25a formed on the rider 23a and cooperating with cams 25b attached to the fan case 14. The action is similar, the cams functioning to cause the rider to move radially in response to circumferential movement.

20 In the form shown in Fig. 12 the roller 24a is attached to the fan case and rides against an arcuate bracket member 20a which carries the wheels 19. The arcuate face against which the roller 24a rides is concentric with the axis of 25 swinging movement of the fan case so that the fan case may be oscillated without disturbing the height adjustment, which is controlled by the radial position of the roller 24 mounted on a bell crank lever 36 fulcrumed at 37 upon the fan 30 case. The control wire 28 is attached to the other end of the lever. A spring 38 urges the bell crank lever in a direction to move the roller 24a toward the fan case.

In all of the forms of the invention heretofore 35 described height adjustment may be indicated with the upper end of the handle.

In the form shown in Figs. 8 and 9 the adjustment may be effected from, but not indicated at, the upper end of the handle. Adjustment is effected by simply moving the wire 28 40 through a single range of movement sufficient to cause the slidably mounted finger 39 to engage a pair of bell crank levers 40 which are formed integrally with a pair of retracting bolts 41 rotatably mounted in the bracket 20b. A 45 teat 42 formed in the bracket 20b engages the screw groove 43 of each bolt 41 and causes the bolt to be retracted when the levers 40 are pushed forwardly so as to remove the bolts from their connection with holes 44 in the brackets 22a. The brackets 22a are secured to the throat members 12 and serve both as the hinge of the brackets 20b at 21 and as keepers to receive the bolts 40.

50 The finger 39 has a slide portion 45 slidably mounted in a slideway 46 on the fan case and embracing the peripheral bead 32.

In the operation of this form of the invention, the pull upon the wire 28 causes the arm 39 to move the bell crank lever to a position to retract the bolts 41. The bracket 20b is then free to move around its hinge axis 21 in accordance with pressure exerted upon the fan case by the operator either to depress the same or to lift it up.

55 The pressure to lift the fan case upwardly will be supplied by a spring 47 urging the bracket 20b downwardly. The pressure to move the fan case downwardly, of course, will be provided by the operator's bearing down on the handle. Utilizing these two opposing forces the operator may cause the bracket 20b to move from one position to another of the four positions in which the bolts 40 may engage and lock in the apertures 44 in the bracket 22a.

70 In the form shown in Figs. 10 and 11 the po-

sition of the bracket 20b is determined by telescoping spring repelled plungers 50 engaging depressions 51 in the brackets 22a. Adjustment of the bracket 20b in one direction is provided by a bell crank lever 52, one end of which is adapted to engage the bracket 20b and the other end of which is attached to the wire 28. The position of radial projection of the lever 52 determines the position to which the bracket 20b will be pushed when the handle is moved downwardly to bring the bracket 22 in operative engagement with the bracket 20b. The lever 52 is operative for moving the bracket 20b downwardly. For causing it to move upwardly the operator may simply bear down upon the handle while holding it in both hands causing the fan case and the hinge 21 to move downwardly relative to the wheels 19.

75 It will be seen that the invention in all of its forms provides adjusting mechanism which is largely concealed below the fan case and a control mechanism operated from the upper end of the handle including a flexible wire extending down through the handle substantially tangent to the periphery of the fan case, thence between the cape member 17 and the fan case, slidingly bearing against the periphery of the fan case and thence attached to the adjusting mechanism. This solves a problem which would be present if the wire 28 were forced to travel around a sharp corner, namely, that of the destructive action of bending, that of the resistance to movement caused by the sharp bending, and that of arranging the adjusting mechanism in an inconspicuous location.

80 I claim as my invention:

1. In a vacuum cleaner, a body portion, a fan case rotatably attached thereto on a transverse horizontal axis, and disposed in a longitudinal vertical plane, a handle rigidly attached to the fan case, adjustable means supporting said body portion, and control means including a flexible element extending through the handle and around a portion of the periphery of said fan case, for effecting adjustment of said supporting means.

85 2. In a vacuum cleaner, a body portion, a fan case attached thereto on a transverse horizontal axis and disposed in a longitudinal vertical plane, a handle attached to the fan case, adjustable means supporting said body portion and control means including a flexible element extending through the handle and around a portion of the periphery of said fan case, for effecting adjustment of said supporting means.

90 3. In a vacuum cleaner, a body portion, a fan case rotatably attached thereto on a transverse horizontal axis and disposed in a longitudinal vertical plane, a handle rigidly attached to the fan case, adjustable means supporting said body portion, and means for effecting adjustment of said supporting means, including a pull element extending along the handle, said pull element having a flexible portion extending around a portion of the periphery of said fan case.

95 4. In a vacuum cleaner, a body portion, a fan case attached thereto on a transverse horizontal axis and disposed in a longitudinal vertical plane, a handle rigidly attached to the fan case, adjustable means supporting said body portion, and means for effecting adjustment of said supporting means, including a pull element extending along the handle, said pull element having a flexible portion extending around a portion of the periphery of said fan case.

5. In a vacuum cleaner, a body portion, a handle assembly swingingly attached thereto, adjustable means for supporting said body portion, and means for effecting adjustment of said supporting means, comprising a flexible adjusting member attached to the handle assembly and adjustable radially of the axis of swinging movement thereof, and a cooperating member attached to the supporting means, one of said members having a working face arcuately disposed substantially concentric with the axis of swinging movement of the handle, and the other of said members being in travelling engagement with said working face, its position determined by the position of adjustment of said adjusting member but substantially unaffected by swinging of the handle assembly. 5
- 10 6. In a vacuum cleaner, a body portion, a handle assembly swingingly attached thereto, adjustable means for supporting said body portion, and means for effecting adjustment of said supporting means, comprising an adjusting member attached to the handle assembly and adjustable radially of the axis of swinging movement thereof, and a cooperating member attached to the supporting means, one of said members having a working face arcuately disposed substantially concentric with the axis of swinging movement of the handle, and the other of said members being in travelling engagement with said working face, its position determined by the position of adjustment of said adjusting member but substantially unaffected by swinging of the handle assembly. 10
- 15 7. In a vacuum cleaner, a body portion, a handle assembly swingingly attached thereto, adjustable means for supporting said body portion, and means for effecting adjustment of said supporting means, comprising a flexible adjust- 15
- 20 8. In a vacuum cleaner, a body portion, a handle assembly swingingly attached thereto, adjustable means for supporting said body portion, and means for effecting adjustment of said supporting means, comprising an adjusting member attached to the handle assembly and adjustable radially of the axis of swinging movement thereof, a cooperating member attached to the supporting means, one of said members having a working face arcuately disposed substantially concentric with the axis of swinging movement of the handle, and the other of said members being in travelling engagement with said working face, its position determined by the position of adjustment of said adjusting member 20
- 25 but substantially unaffected by swinging of the handle assembly, and means for determining the position of adjustment of said adjusting member, comprising an operating device at the upper end of the handle and a flexible pull element extending along the handle from said operating device to said adjusting member. 25
